DUPLICATING APPARATUS

Wilhelm Ritzerfeld, Berlin, Germany

Application October 8, 1935, Serial No. 44,076.
Renewed September 4, 1937. In Germany October 8, 1934

9 Claims. (Cl. 101—132)

The present invention relates to duplicating apparatus, and more particularly to a new method of working and a special form of embodiment of a machine for re-printing book-
5 keeping entries or the like, comprising one or more lines to be copied from an original sheet or printing plate furnished with reverse characters, signs on to sheets, cards etc., which have previously been covered with a very thin film of a
10 volatile solvent, as spirit or the like.

In the hitherto known manifolding machines for line by line or sectional re-printing only a copying step-by-step of the single lines from an original, which was attached to a printing drum
15 with the lines of matter arranged vertically to the drum axis, was performed in such a way, that after the re-printing of one line of the original sheet had taken place the next line had to be copied.

20 The most important feature of the present invention is the method of re-printing single lines step by step or in any desired succession. This is necessary for printing material lists, salary bags or the like. A further object of the invention is
25 the device permitting to re-print any desired line at will of an original or printing plate attached to the printing drum with the lines of matter arranged vertically to the drum axis.

30 This device consists of an arrangement of automatically or manually driven elements for lateral displacement of a special member, carrying a counterpressure roller, a moistening device, both of line width and a feeding table. This member is moved sideways on an axis parallel to the axis of the printing drum step by step or at will in any desired succession of lines.

35 Further features of the invention may be seen from the drawings which show diagrammatically one embodiment of the invention and in which the same reference characters have been used in all the views to indicate corresponding parts.

40 Fig. 1 is a side view

Fig. 2 is a front elevation

45 Fig. 3 is a detail of the device according to the invention.

Between the sidewalls 15 the printing drum 1 is provided. To said drum 1 an original sheet or printing plate is attached. The sheet to be printed upon—the copy sheet—is to be fed between said drum 1 and a counterpressure roller 2, which is pressed in any desired manner against said drum 1 and which thus effectuates the copying from the original sheet. On the axis 6' parallel to the axis of the printing drum 1 a member 6 is slidable in both directions.

This sliding member 6 carries a rotatable and pivotable counterpressure roller 2 of single line width, furthermore a moistening device, consisting of the reservoir 10, the moistener 9 with the protruding felt 11 and a feeding table 8 for feeding the sheets or cards to be printed upon towards the bight of the drum 1 and the counterpressure roller 2. The feeding table 8 is attached to the sliding member 6 by a holding member 6'' the length of which is adjustable in such a manner that sheets of any desired size may be fed to the apparatus. At the lower part of the sliding member 6 a rack is rigidly attached parallel to the aforesaid axis 6'.

To the left said member 6 is slidable by a tension means, which is coiled up in an anticlockwise direction by a spring provided in the box 51. To the right said member 6 is movable by working a crank 53 turning the axis 52, which acts upon the ratchet wheel 54, preferably secured in a box.

At one sidewall 15, on brackets, not shown in the drawings, two bell crank levers 57 and 58 are horizontally pivoting around 55 and 56. Two connecting rods 59 and 60 directed to the left in the embodiment of the invention as shown in the drawings, are attached to those arms of the bell crank levers 57 and 58 which are parallel or nearly parallel to the sidewall 15. In 51, pivotable around 63, the pawl 62 is provided. One arm of this pawl 62 is elongated and carries, pivoting in 64, the second pawl 65, to which in 66 the connecting rod 60 is attached, the other end of said connecting rod 60 being joined to lever 58. The position of the two pawls 62 and 65 is provided in such a manner, that they are capable of engaging the teeth of rack 50. The way of these pawls 62 and 65 is determined and limited by springs 76 and 77. The free arms of the bell crank levers 57 and 58 are in touch with the arms of the key-levers 67 and 68 pivoting around 40 the axis 69.

For automatic lateral displacement of the sliding member 6 a cam 70 attached at the front side of the printing drum 1 strikes against one arm of a bell crank lever 71 pivoting around 72, to which a connecting rod 73 is joined, the other end of which is connected to lever 57. A lever 75 pivoting around 74 enables the setting out of work of the aforesaid device.

The way of operation of the contrivance is the following: If the key lever 68 is pulled downwards the bell crank lever 57 is pivoted in an anticlockwise direction and pushes the connecting rod 59 to the right thus engaging pawl 62 with rack 50. In the meantime the pawl 65 is 55

disengaged by this movement from rack 50 and the sliding member 6, attached to said rack, and all the parts attached to it, as counterpressure roller, reservoir for the solvent, the moistener 5 with the protruding felt, and the feeding table travel one step of the width of a line to the left by means of the coil spring in the box 51. If several lines are to be left out the key lever 67 is pulled downwards. By its action the bell 10 crank lever 58 is pivoted in an anticlockwise direction, the connecting rod is pushed to the left and the pawl 65 is disengaged from rack 50 whilst pawl 62 remains out of contact with said rack 50. Now the sliding member 6 travels by 15 tension of the coil spring in box 51 to the left until key lever 67 is given free, whereupon the pawl 65 engages again with rack 50.

The device can be actuated manually, electrically or pneumatically. The position of the 20 single elements of said device may be adapted to any desired requirements.

What I claim as new and desire to secure by Letters Patent is:

1. In a duplicating machine printing onto clear 25 sheets previously moistened with a readily volatilizing solvent, the combination comprising a rotatable printing roller bearing a copyable mirror-script original constituted of a plurality of lines arranged in the direction of rotation of said 30 roller, a sliding member adapted to be displaced in a direction parallel to the axis of said printing roller, a moistening means, a counterpressure roller and a feeding table associated with said 35 sliding member and adapted to co-operate with said printing roller to selectively copy a portion of said original onto a copy sheet in accordance with the position of said sliding member, a powered rack connected to said sliding member, means for engaging said rack to prevent 40 displacements thereof, and means for moving said engaging means into an inoperative position to disengage said rack and to permit said sliding member to be displaced into a position corresponding to the length of time during which said 45 rack is disengaged.

2. In a duplicating machine printing onto clear 50 sheets previously moistened with a readily volatilizing solvent, the combination comprising a rotatable printing roller bearing a copyable mirror-script original constituted of a plurality of lines arranged in the direction of rotation of said roller, a sliding member adapted to be displaced in a direction parallel to the axis of said printing roller, a moistening means, a counterpressure roller and a feeding table associated with 55 said sliding member and adapted to co-operate with said printing roller to selectively copy a portion of said original onto a copy sheet in accordance with the position of said sliding member, a spring-powered rack connected to said sliding member and extending in the direction of movement thereof, a pair of pawls adapted to alternately engage the teeth of said rack to retain 60 said sliding member, and means for selectively disengaging said pawls for causing displacements of said sliding member by any desired amount.

3. In a duplicating machine printing onto clear 65 sheets previously moistened with a readily volatilizing solvent, the combination comprising a rotatable printing roller bearing a copyable mirror-script original constituted of a plurality of lines arranged in the direction of rotation of said roller, a sliding member adapted to be displaced 70 in a direction parallel to the axis of said print-

ing roller, a moistening means, a counterpressure roller and a feeding table associated with said sliding member and adapted to co-operate with said printing roller to selectively copy a portion of said original onto a copy sheet in accordance 5 with the position of said sliding member, a spring-powered rack connected to said sliding member and extending in the direction of movement thereof, a pair of pawls adapted to be actuated to alternately engage and disengage a tooth 10 of said rack, means for alternately actuating said pawls to cause step by step displacement of said sliding member, and means for simultaneously disengaging both of said pawls to cause continuous displacement of said sliding member. 15

4. In a duplicating machine printing onto clear sheets previously moistened with a readily volatilizing solvent, the combination comprising a rotatable printing roller bearing a copyable mirror-script original constituted of a plurality of lines 20 arranged in the direction of rotation of said roller, a sliding member adapted to be displaced in a direction parallel to the axis of said printing roller, a moistening means and a counterpressure roller of single line width and a feeding table ad- 25 justably mounted on said sliding member and adapted to co-operate with said printing roller to selectively copy one line of said original onto a copy sheet in accordance with the position of said sliding member, a powered rack connected to 30 said sliding member and extending in the direction of movement thereof, a pivoted pawl engaging a tooth of said rack, a second pawl pivotally mounted on said first pawl and adapted to engage another tooth of said rack, and means for 35 selectively disengaging said pawls to cause step by step and continuous displacement of said sliding member.

5. In a duplicating machine having a printing roller bearing a copyable mirror-script original, 40 the improvement comprising a displaceable member adapted to be moved in a direction parallel to the axis of said printing roller, feeding, counterpressure and moistening means associated with said member and adapted to co-operate with said 45 roller to print a portion of said original onto a copy sheet according to the position of said displaceable member, means for moving said displaceable member, means for locking said displaceable member against the effect of said moving means, and means for making said locking 50 means inoperative for a limited time to cause displacement of said member by said moving means.

6. In a duplicating machine printing onto clear sheets previously moistened with a readily volatilizing solvent, the combination comprising a rotatable printing roller adapted to hold a master sheet bearing lines in copyable mirror-script arranged in the direction of rotation of said roller, pressure means for pressing a portion of a clear 60 sheet against said master sheet, means for moistening said clear sheets, said pressure and moistening means being adapted to be displaced in a direction parallel to the axis of said printing roller, means for displacing said pressure and moistening means, means for locking said pressure and moistening means against the effect of said displacing means, automatic releasing means including a cam on said printing roller and a lever system for making said locking means inoperative 65 for a limited time during each rotation of said printing roller, means for displacing said pressure and moistening means, means for locking said pressure and moistening means against the effect of said displacing means, automatic releas- 70 75

ing means including a cam on said printing roller and a lever system for making said locking means inoperative for a limited time during each rotation of said printing roller, manually operable 5 releasing means including a lever system for making said locking means inoperative, and means for selectively actuating said automatic and said manually operable releasing means for causing displacement of said pressure and moistening means.

7. In a duplicating machine printing onto clear sheets previously moistened with a readily volatilizing solvent, the combination comprising a rotatable printing roller adapted to hold a master sheet bearing lines in copyable mirror-script arranged in the direction of rotation of said roller, a feeding table for feeding clear sheets to said printing roller, pressure means for pressing a portion of a clear sheet against said master sheet, 15 means for moistening said clear sheets, said pressure and said moistening means being adapted to be displaced in a direction parallel to the axis of said printing roller, means for displacing said pressure and moistening means, means for locking said pressure and moistening means against the effect of said displacing means, automatic releasing means for making said locking means inoperative for a limited time during each rotation of said printing roller, manually operable 20 releasing means for making said locking means inoperative, and means for selectively actuating said automatic and said manually operable releasing means for causing displacement of said pressure and moistening means.

8. In a duplicating machine printing onto clear sheets previously moistened with a readily volatilizing solvent, the combination comprising a rotatable printing roller adapted to hold a master sheet bearing lines in copyable mirror-script arranged in the direction of rotation of said roller, a feeding table for feeding clear sheets to said printing roller, pressure means for pressing a portion of said clear sheet against said master 25

sheet, means for moistening said clear sheet, said pressure and said moistening means being adapted to be displaced in a direction parallel to the axis of said printing roller, means for displacing said pressure and moistening means, means for locking said pressure and moistening means against the effect of said displacing means, automatic releasing means for making said locking means inoperative for a limited time during each rotation of said printing roller, manually operable 30 releasing means for making said locking means inoperative, and means for selectively actuating said automatic and said manually operable releasing means for causing line by line and step by step displacement of said pressure means 35 and of said moistening means.

9. In a duplicating machine printing onto clear sheets previously moistened with a readily volatilizing solvent, the combination comprising a rotatable printing roller adapted to hold a master sheet bearing lines in copyable mirror-script arranged in the direction of rotation of said roller, a sliding member adapted to be displaced in a direction parallel to the axis of said printing roller, moistening means and counterpressure 40 means associated with said sliding member for moistening a portion of a clear sheet and to press said portion against the printing roller, a feeding table for introducing clear sheets between said printing roller and said counterpressure means, means for displacing said sliding member, means for locking said sliding member against the effect of said displacing means, automatic releasing means operated by said printing roller for making said locking means inoperative for 45 a limited time during each rotation of said printing roller, manually operable releasing means for making said locking means inoperative, and means for selectively actuating said automatic and said manually operable releasing means for 40 causing line by line and step by step displacement of said sliding member.

WILHELM RITZERFELD.
